UNITED STATES PATENT OFFICE.

STEVE BULLUM AND WILLIAM O. MAXWELL, OF LOS ANGELES, CALIFORNIA.

SPUDDING JACK.

1,409,438.

Specification of Letters Patent. Patented Mar. 14, 1922.

Application filed February 12, 1919. Serial No. 276,693.

To all whom it may concern:

Be it known that we, STEVE BULLUM and WILLIAM O. MAXWELL, citizens of the United States, residing at Los Angeles, in the county 5 of Los Angeles and State of California, have invented new and useful Improvements in Spudding Jacks, of which the following is a specification.

Our object is to make a spudding jack, 10 and our invention consists of the novel features herein shown, described and claimed.

The principal objects to be attained by this invention are:

First: a shock absorbing device between 15 the point at which the power is applied (band wheel crank) and the other portions of the rig and machinery. It has been customary heretofore to use, instead of a device of this nature, a section of manila or wire 20 cable, called a jerk line, which was connected with the band wheel crank by means of a collar commonly known as a spudding ring, and thence extending in one solid piece to a connection with a spudding shoe which was 25 fitted to the drilling cable. This jerk line device was anchored down to the rig foundation at the same point as the anchor connection shown in this application, except that for this purpose a section of cable was used 30 instead of the hook rod and eye bolt as specified herein. So long as a manila drilling cable was used for spudding the well in or getting the hole started there were no serious objections to the old jerk line method as the 35 manila drilling cable allowed for sufficient spring or give to absorb a large part of the shock resulting from the drilling motion. However, manila drilling cables have now gone out of general use in well drilling work, 40 giving way to steel wire cable, which is much more rigid in its reaction from a shock such as results from a drilling motion. This rigidity and resultant shock is very severe on the mechanical construction of the drilling machinery generally, and one of the 45 principal objects of our device is to take this shock from the rig by means of a shock absorbing spring.

Second: the wheel device 14 rolls or turns 50 while in contact with the drilling cable, which feature we claim to be an improvement over the spudding shoe method now in common use and which required the drill-

ing cable to slide against the face of the spudding shoe.

Figure 1 is a side elevation of a well rig showing our spudding jack in use.

Fig. 2 is an enlarged perspective of the spudding jack.

Fig. 3 is an enlarged cross sectional detail 60 on the line 3—3 of Fig. 2.

Fig. 4 is an enlarged sectional detail on the line 4—4 of Fig. 2.

Fig. 5 is a top plan view of the intermediate joint as seen looking in the direction 65 indicated by the arrow 5 in Fig. 2.

The drill or spudding tool is connected to the lower end of the rope 1 down in the well 2, and the rope 1 runs over the guide pulley 3 at the top of the derrick and down and is 70 attached to and wound upon the bull wheel 4. A band wheel 5 is mounted upon a shaft 6, and a crank arm 7 is fixed upon one end of the shaft 6. A crank pin 8 is fixed in the crank arm 7 and a grooved roller 9 is mounted upon the crank pin. The spudding jack 10 connects the roller 9 to the downwardly extending portion 11 of the rope 1, so that as the band wheel 5 rotates the jack is operated to pull the portion 11 of the rope to 80 raise and lower the drill or spudding tool.

A bar 12 has a bearing arm 13 offset and extending from its outer end. A grooved pulley 14 fits against the inner face of the bearing 15 at the outer end of the arm 13, a removable arm 16 has an offset portion 17 fitting against the straight portion of the bar 12, and a bearing 18 at its opposite end, said bearing 18 fitting against the pulley 14. A bolt 19 connects the offset portion 17 to the 85 body of the bar 12. A pin 20 is inserted through the bearing 18 and through the pulley 14 and through the bearing 15, there being a shoulder 21 upon the pin to hold the pulley 14 against the bearing 15. A cotter 22 is inserted through the end of the pin 20 outside of the bearing 15 to hold the pin in place, thereby holding the pulley 14 in place. The bearing 18 is removably mounted upon the head 23 of the pin against the pulley 14, 90 and a cotter 24 is inserted through the head 23 outside of the bearing 18.

When it is desired to place the portion 11 of the rope in the passage 25 between the arms 13 and 16 against the pulley 14, the cotter 24 is removed, the nut 26 is screwed out-

wardly upon the bolt 19 and the arm 16 moved outwardly beyond the head 23 and swung upon the bolt, so that the rope may be placed in position; then the arm 16 is swung 5 backwardly and the bearing 18 placed upon the head 23 and the nut 26 tightened.

At the opposite end of the bar 12 from the pulley 14 arms 27 and 28 are made to form a bifurcated bearing, and the extension arm 10 29 extends from the arm 28 and has a hook 30 upon its extreme end. The rod 31 is mounted in the bifurcation between the arms 27 and 28 in line with the hook 30. The anchor rod 32 has a bifurcated bearing 33 at 15 its upper end to straddle the arms 27 and 28, and a pivot pin 34 is inserted through the bearing 33 through the arms 27 and 28 and through the rod 31. The hook 30 swings downwardly from the rod 31 and 20 will not pass upwardly beyond the rod. A hook 35 is formed at the lower end of the anchor rod 32. An eye bolt 36 is fastened in the sill 37, and the hook 35 engages the eye of the bolt 36 so as to limit the upward 25 swing of the rods 12 and 31. An eye bolt 38 is inserted through the post 39 and a hook 40 is connected to the eye bolt to swing upwardly and engage the hook 30 when desired.

30 A crosshead 41 is mounted upon the opposite end of the bar 31 from the joint, a spring 42 is mounted upon the bar 31 against the crosshead 41, a second crosshead 43 is slidingly mounted upon the bar 31 against 35 the spring, and a U-shaped yoke having a central portion 44 and side bars 45 and 46 is mounted with the side bars 45 and 46 sliding through the crosshead 41 and extending through the crosshead 43 with nuts 40 47 and 48 upon the ends of the side bars 45 and 46 against the crosshead 43.

The tension of the spring 42 is exerted to press the crossheads 41 and 43 apart. The circular central portion 44 engages the 45 grooved roller 9, and the tension upon the rope 1 and the tension of the spring 42 is exerted to hold this curved central portion 44 in the groove when the band wheel is running. When the parts are moved to 50 proper position the hook 40 may be swung upwardly to engage the hook 30; then the band wheel may be backed up slightly thus moving the roller 9 out of engagement with the curved portion 44; then the side bars 55 45 and 46 will pass over the rim of the roller and the jack is disconnected from the band wheel.

The hook 40 engaging the hook 30 will hold the pulley 14 against the tension of the 60 rope; while the jack is disconnected from the band wheel, and as soon as the connection is made to the band wheel and the band wheel started the tension on the hook 40 will be released and the hook 40 will fall. Continued operation of the band wheel will

make a bend in the portion 11 of the rope at each revolution of the band wheel, thereby raising the drill or spudding tool and then the rope will straighten and allow the tool to fall.

70 The anchor rod 32 holds the bars 12 and 31 from vibrating up and down and makes a steady pull on the bar 12 at a practically steady angle. The spring 42 serves as a shock absorber and makes a yielding connection between the crank pin 7 and the rope portion 11.

75 Our spudding jack takes the place of the rope usually employed.

The principal object of our spudding jack 80 is to provide a shock absorbing connection between the band wheel and the rope. The rigid connections heretofore in use have been short lived on account of their rigidity and this fault has not only made the connection 85 short lived, but it has made the operation noisy and objectionable and injurious to the other parts of the rig.

Various changes may be made without departing from the spirit of our invention 90 as claimed.

We claim:

1. A spudding jack comprising a pulley adapted to run upon a rope, a bar extending from the pulley, a second bar hinged to the first bar, an anchor rod pivotally connected at its upper end to the hinge joint between said bars, the lower end of said anchor rod being pivotally connected to a fixed part of the derrick, a crosshead fixed upon the opposite end of the second bar from the hinge joint, a second crosshead slidingly mounted upon the second bar, a spring between the crossheads, and means for connecting the sliding crosshead to the crank pin of a band 95 wheel.

2. A spudding jack comprising a pair of rods hinged to each other at their inner ends, an extension on the inner end of one of said rods for engaging the opposite rod 100 to limit the upward movement of the hinged ends of said rods, a pulley carried by the outer end of one of the rods, a loop yieldingly mounted on the outer end of the other rod, a spring for resisting the outward 105 movement of said loop upon said rod, and an anchoring rod pivotally connected to the hinge joint between the inner ends of said rods.

3. A device for the purpose of imparting motion to drilling tools by means of a connection from the crank pin of a band wheel to the cable on which the drilling tools are suspended, comprising a rolling wheel in contact with the drilling cable, a resilient 120 connecting means for the wrist pin of the band wheel, a jointed rod connecting the rolling wheel with the connecting means on the wrist pin, and a separate anchoring rod pivotally connected to and extending down- 125 130

wardly from the joint of the connecting rod and anchored below said joint.

4. A spudding device for well drilling apparatus, comprising three rods hinged to each other at their inner ends, a pulley journaled at the outer end of one of said rods, a yieldingly mounted loop at the outer end

of another one of the rods, and a hook at the outer end of the third rod.

In testimony whereof we have signed our names to this specification.

STEVE BULLUM.
WM. O. MAXWELL.
